YARN LUBRICATION

Malcolm H. Lyle, Johnson City, and Clifton E. Smith, Elizabethton, Tenn., assignors to North American Rayon Corporation, New York, N. Y., a corporation of Delaware

Application February 18, 1942, Serial No. 431,328

11 Claims. (Cl. 117—115)

This invention relates to a method of and apparatus for continuously applying a controlled quantity of liquid, such as oil or other liquid agent, to a textile thread while the thread is being wound onto a cone, cap, or the like at variable linear speeds.

In winding machines, the cores upon which the thread is wound are commonly driven at a constant speed during the entire winding operation. As the yarn body is built up in overlying layers on the core, the diameter of the yarn body increases constantly. Consequently, the linear speed of the thread increases progressively in proportion to the increase of the diameter of the yarn body. When lubricants, dyes or other finishing liquids are applied to such travelling threads, the amount of liquid applied to a unit length of thread is not constant, because the amount of liquid applied per unit length of thread is much less when the diameter of the package is large and therefore the linear speed of the thread is great, than is the case when the diameter of the package is small. In order to produce a uniformly wound and treated package on such machines, it is necessary to control the rate of liquid supply in accordance with the linear speed of the thread and to maintain the thread under uniform tension throughout the winding operation. The lubricant or other dressing liquid should preferably be applied continuously, at a controlled rate, and in such a manner as not to affect the tension of the thread.

Various devices for the control of the liquid supply have been employed heretofore which, however, have not given satisfactory results. A device most commonly used for this purpose at the present time consists of a rotating roller which is partially immersed in a liquid bath and over which the thread is passed in order to apply the treating solution thereto. As the winding operation progresses and the linear speed of the thread increases, the position of the thread on the roller is progressively changed so as to extend the arc of contact of the thread with the roller and thus increase the rate of liquid supply to the thread. However, this device, besides yielding a non-uniformly treated thread, causes variations in the thread tension due to the progressively increasing drag of the thread as a result of the increase in length of contact of the thread with the roller as the build up of the yarn package on the core progresses.

It is therefore, an object of the present inven-

tion to provide for the uniform treatment of the thread throughout the winding operation.

Another object of the invention is to provide a device which is adapted to control the rate of liquid supply in accordance with the linear speed of the thread so as to maintain a uniform distribution of the liquid over the entire length of the thread.

A further object is to provide a device which is adapted to continuously wet-treat a thread with an amount of liquid directly in proportion to the linear speed of the thread and without affecting the tension of the thread.

Still another object is to provide a device of the type indicated for use with standard types of winding machines wherein the yarn is wound on a support or holder having a constant speed of rotation with the linear speed of the yarn increasing as the package grows in diameter.

Other objects and advantages of the invention will be apparent during the course of the following description when studied in conjunction with the accompanying drawings, in which:

Fig. 1 is a front elevation of a thread lubricating arrangement showing the device of the present invention in operative position.

Fig. 2 is a side elevation of Fig. 1 partially in cross section;

Fig. 3 is a front view of the device comprising the present invention;

Fig. 4 is a top view of Fig. 3;

Figs. 5 and 6 are cross-sectional side views taken along lines 5—5 and 6—6, respectively, of Fig. 3;

Fig. 7 is a front elevation of two winding units of a conventional winding machine illustrating the relative position of the parts near the beginning and end, respectively, of a winding operation, and

Fig. 8 is a top plan view of the thread-lubricating device.

Like reference numerals denote like parts in the various figures of the drawings.

In the following description and in the claims various details will be identified by specific names for convenience, but they are intended to be as generic in their application as the art will permit.

Referring to the drawings more in detail, the invention is shown as embodied in a winding machine adapted to receive threads 8 from suitable supply sources such as spools, cakes, or the like, not shown; to treat the threads with a suitable liquid dressing by means of a liquid suspension device 9 which receives the liquid from

a supply means 10 partly immersed in a bath of the liquid; and to wind the threads onto suitable supports 11 (Fig. 7) to form packages such as cones or spools 12 suitable for fabrication.

Inasmuch as the winding machine may include duplicate mechanisms to simultaneously wind and treat a plurality of threads, the description will be confined to a mechanism adapted to cooperate with a single thread. Two such mechanisms have been illustrated in Fig. 7 to show the relative positions of the parts near the beginning and end, respectively, of a winding operation. It is to be understood, however, that the machine will incorporate as many such mechanisms as may be desired.

Referring more particularly to one of the winding mechanisms, the thread 8 is first passed through stationary thread guides 13 and 14, thence through the liquid suspension device 9 and further through a movable thread guide 15. The latter controls the relative position of the path of thread with respect to the liquid suspension device during a complete winding operation. The thread is then passed through a stationary thread guide 16 (Fig. 7), a tensioning device 17, and through a traversing thread guide 18 by which it is directed onto the core or cone 11 which is being wound on the rotating spindle 19.

The spindle 19 is rotatably mounted on a frame 20 of the machine and is adapted to be operated at a constant speed by any suitable driving means, not shown. The traversing thread guide 18 is adapted to move longitudinally of the spindle 19 during the winding operation for causing the thread to be wound thereon in helical courses of progressively increasing diameters. This thread guide is mounted on a support 21 which is pivotally mounted on a shaft 22. The support 21 is provided with a counterweight 23 whereby its upper portion tends to swing toward the axis of the winding spindle and thus maintains the guide 18 in constant contact with the mass of thread on the core 11 during a complete winding operation.

The tensioning device 17 may be mounted on a suitable bracket 17a carried by the frame 20 and may comprise, for example, a pair of comb members 24 between which the thread passes and which are adapted to exert pressure on said thread for applying the necessary tension thereto. Suitable means, well known in the art, may be provided for varying the relative position of the comb members 24 so as to maintain the tension of the thread substantially constant as the speed of travel thereof increases during the winding operation. Depending from the tensioning device 17 is a stationary pig-tail thread guide 16.

The movable thread guide 15 is mounted in a block 26 and is adjustable with respect to the stationary thread guide 14 by means of clamping nuts 27. The block 26 is adapted to slide on a bar 25 which extends longitudinally of the machine and parallel to the axis of the roll 10. The block 26 supporting the thread guide 15 is moved along the bar 25 by means of a link 28 one end of which is connected to a perforated ear 29 on the block 26 while its other end engages an arm 30 carried by the counterweight 23 of support 21. The arm 30 may be pivoted to said support 21 as at 31 and may be held in adjusted position by means of a set screw 32 passing through an elongated slot 33 in said arm. The lower end of arm 30 is provided with a series of spaced holes 34, to any one of which the link 28 may be coupled to adjust the

relative extent of lateral movement of the thread guide 15 on the bar 25.

The moistening or emulsifying device comprises a trough 35 which extends the whole length of the machine below the winding spindles and which may be supported on the frame of the machine in any suitable manner. The trough 35 is adapted to contain a liquid indicated at 36, for example, an emulsion having an oil base, or any other suitable conditioning solution in accordance with the requirements of the material to be treated. Partially immersed in the liquid 36 is a liquid feeding element herein illustrated as a small cylinder or contact roll 10 carried on a shaft 37. The shaft 37 is rotatably journaled in suitable bearings 38 at the ends of the trough 35, and at one end of the shaft is a stepped pulley 39 adapted to be driven from a belt or band 40 connected to a driving element of the winding machine. The shaft 37 is driven to rotate the roll 10 at a suitable speed to maintain the surface of the roll wetted to the proper degree from the bath of fluid or emulsion 36 in the trough 35.

Mounted in bearing lugs 41 at the forward side 25 of the trough 35 and below the axis of the roll 10 is a bar 42 carrying a stationary thread guide 14. By rocking the bar 42 in the bearing lugs 41, the position of the thread guide 14 may be adjusted so as to control the path of the thread 30 through the liquid suspension device 9 and through the movable thread guide 15. The bar 42 is held fixed in its adjusted position by means of set screws 43 in the bearing lugs 41. Stationarily mounted on the trough 35 and substantially 35 in axial alignment with thread guide 14 and in spaced relation thereto is a thread guide 13 which is adapted to stabilize the path of the thread coming from a supply source (not shown) prior to its 40 passage through the thread guide 14 and liquid receptacle 9.

Mounted on the trough 35 and positioned in front of the roll 10 is the liquid suspension device 9. This device consists of a bracket 44, one end 45 of which is secured to the trough 35 by means of screws 45 extending through slots 46 which are adapted to permit limited lateral adjustment of the liquid suspension device with respect to the roll 10. The other end of the bracket 44 pivotally supports a link 47 by means of a bolt 48. Mounted on the link 47 and extending outwardly to one side thereof is the liquid suspension device 9 consisting of two spaced substantially triangular blades A and B of substantially uniform length and width with respect to one another. These blades are positioned in spaced relation one above the other; the upper blade A being secured to the link 47 by means of screws 50 extending through slots 51 in the link 47. Slots 51 permit up and down adjustment of the position of the liquid suspension device 9 with respect to the link 47. The lower blade B is secured to the blade A by means of screws 52 and is held in uniformly spaced relation thereto by means of a spacer plate 53 (Figs. 4, 5 and 8). These two blades thus cooperate to form a slot 49 of capillary dimensions as best illustrated by Fig. 4, through which the thread passes on its way to the support 11 upon which it is wound. As shown in Fig. 4, the unsupported end portion 54 of the blade A is bent inwardly toward the blade B so as to narrow the width of the slot 49 at this point and thus assist in the feeding of the liquid thereto.

Extending arch-like outwardly from both ends

of blade B and angularly inclined with relation thereto is a scraper 56 comprising two liquid guiding surfaces 58 and 59 having angularly disposed edges 60 and 61, respectively, and a knife-like edge 57 adapted to contact the surface of roll 10 and to receive liquid therefrom as the latter rotates partially immersed in a bath 36 contained in a trough 35. Owing to the inclined position of the scraper 56 with respect to roll 10, the liquid lifted from the roll 10 by the edge 57 will be caused to flow along the guiding surfaces 58 and 59 restricted by sloping edges 60 and 61, respectively, and will thus be fed into both ends of the capillary slot 49 between the blades A and B where it is held in suspension substantially in the form of a sector of a cylinder. Surfaces 58 and 59 differ in size and thus a greater quantity of liquid will be fed into the wide portion of the slot 49 by the large surface 58 while the shorter surface 59 will feed a proportionately smaller amount into the comparatively narrow portion of the slot 49, i. e., the apex end of the triangular blades A and B. Depending upon the capillarity of the liquid employed in the treatment of the thread, the width of the bath suspended in the slot 49 may be adjusted so as to vary the quantity of liquid applied to the thread. This adjustment may be accomplished by using thicker or thinner spacer plates 53 in accordance with the requirements. Extensions 62 and 63 of the surfaces 58 and 59, respectively, are provided for the purpose of facilitating the discharge of excess liquid.

The operation of the emulsifying device comprising the present invention is as follows. A thread 8 coming from a supply source such as a spool, cake or the like (not shown) passes through stationary thread guides 13 and 14, thence through the slot 49 in the liquid suspension device 9, through a movable thread guide 15, another stationary thread guide 16, a tensioning device 17, and through a traversing thread guide 18 by means of which it is directed onto the cone core 11 rotated by the spindle 19 on which it is progressively built up into a yarn body 12.

The liquid treatment of the thread takes place within the slot 49 formed by blades A and B of the liquid suspension device 9 in which a treating bath is suspended by capillarity. Upon rotation of the roll 10 partly immersed in a bath 36 treating liquid is constantly lifted from the surface of the roll by means of the edge 57 of the scraper 56. The latter's surfaces 58 and 59 feed the liquid into the slot 49 where a suspended liquid bath in the shape of a sector of a cylinder is constantly maintained and through which the thread 8 travels substantially parallel to the surface of the lower blade A. In order to control the path of the thread through the liquid receptacle in such a manner that contact of the thread with the blades A and B is prevented, thread guides 14 and 15 are adjustable with respect to each other.

Fig. 7 of the drawings illustrates two winding units of a conventional winding machine showing the relative position of the various parts near the beginning and end, respectively, of a winding operation. Since the spindle 19 is rotated at a constant speed, and since the yarn body 12 constantly increases in diameter as the winding operation progresses, the linear speed of the thread increases progressively in proportion to the increase in diameter of the yarn body. In order to produce a uniformly lubricated thread, the supply of treating liquid to the thread must be increased in proportion to the rate of increase

in the linear speed of the thread. This result is obtained in accordance with the present invention through the employment of a suspended liquid bath of varying width, i. e., substantially in the shape of a sector of a cylinder, and by continuously shifting the thread path in the direction of greatest width of said bath at a rate proportional to the rate of increase in the linear speed of the thread. As is shown in Figs. 3, 4 and 8, the liquid suspension device 9 consists of two substantially triangular blades A and B which hold by capillarity a bath substantially in the form of a sector of a cylinder. The thread passes tangentially through this bath in such a manner that it is in contact with the smallest width thereof at the beginning of the winding operation, i. e., when the linear speed of the thread is low, and that it is gradually shifted into portions of the bath of progressively increasing width as the linear speed of the thread increases as a result of the increase in diameter of the yarn package being wound on the spindle.

Fig. 1 illustrates the position of the thread with respect to the liquid receptacle both at the beginning and at the end of a winding operation; the latter position being shown in broken lines. The displacement of the path of thread within the liquid receptacle in proportion to the rate of increase of the linear speed of thread is accomplished in the following manner. A thread 8 is continuously wound at a constant winding speed in overlying layers upon a core 11 (Fig. 7) by means of a traversing thread guide 18. The traversing thread guide 18 is continuously held in contact with the mass of thread on the core 11 by means of a counterweight 28 arranged on a pivotally mounted support 21. As the yarn body 12 on the core 11 increases in diameter in the course of a winding operation, the lower part 40 of the support 21 is constantly swung about its pivot 22 in the direction indicated by the arrow shown in Fig. 7. As a result of this pivotal movement, the thread guide 15 which is connected to the support 21 by means of a link 28 and arm 30 is continuously shifted along the bar 25 to an extent which is in direct proportion to the increase in diameter of the yarn body 12. Since the thread guide 14 is stationary, this displacement of the thread guide 15 causes a constant shifting of the path of thread within the liquid suspension device in the direction of greatest width of the bath suspended therein. Thus, the thread is continuously moved into a constantly increasing width of the bath suspended in the suspension device in direct proportion to the progressively increasing linear speed of thread which results from the increasing thickness of the yarn body as the winding thereof progresses.

Whereas the invention has been described in its preferred form, various modifications may be made without departing from the spirit and scope thereof; and it is to be understood that the invention is only limited to the extent of the appended claims.

What is claimed is:

1. The method of coating thread moving at a continuously increasing linear speed which comprises, passing the thread through a bath of liquid coating material freely held in suspension, said bath being characterized by a regularly increasing width, and continuously shifting the thread path in the direction of greatest width of said bath at a rate proportional to the rate of increase in the linear speed thereof, whereby to

produce thread substantially uniformly coated throughout its length.

2. The method of coating thread moving at a continuously varying linear speed which comprises, passing the thread through a bath of liquid coating material freely held in suspension, said bath being characterized by varying width, and relatively shifting the thread path and the bath to continuously maintain a fixed ratio between thread speed and bath width, whereby to insure substantially uniform coating throughout the length of the thread.

3. Apparatus for the coating of threads comprising, a thread source, a collection device, means for driving the collection device at a constant speed, and means intermediate the thread source and the collection device for applying a coating material to the thread, said means including a receptacle adapted to hold by capillarity a bath substantially in the form of a sector of a cylinder, said receptacle being so disposed with respect to the path of travel of the thread between said thread source and said collection device as to cause said thread to pass through said bath substantially parallel to the base thereof, means for continuously supplying said receptacle with a liquid coating material, and thread guide means for shifting said thread with relation to the receptacle during collection to maintain a fixed ratio between thread speed and bath width at the zone of thread contact, whereby to insure substantially uniform coating of thread throughout its length.

4. Apparatus for the coating of threads comprising, a thread source, a collection device, means for driving the latter at a constant speed, means for suspending by capillarity a bath of varying width, means supporting said suspending means in the path of the thread between said source and said device, means for maintaining a constant supply of liquid coating material in said suspending means, and means responsive to increase in diameter of thread on said collection device for shifting the thread with respect to said bath to maintain a fixed ratio between thread speed and bath width at the zone of contact, whereby to insure substantially uniform coating of thread throughout its length.

5. In apparatus for the coating of thread during a winding operation including a device for the collection of thread at a speed progressively increasing from a minimum at the inception of winding to a maximum at the conclusion thereof, means for suspending by capillarity a bath of liquid coating material in the path of thread moving toward the collecting device, said means being of a width increasing from a minimum to a maximum, the rate of increase in width being a function of thread speed, and thread guide means movable in response to increase in diameter of thread on said collection device for guiding the thread in a path which is shifted into successively wider portions of said bath.

6. The method of coating a thread moving at a constantly increasing linear speed which comprises passing the thread through a liquid coating bath which increases in width toward one end and so varying the relative position of the running thread and the bath that the width of the bath contacted by the thread increases as the linear speed of the thread increases whereby a

coating is produced on the thread which is substantially uniform throughout its length.

5 7. A treating unit for coating a thread running at a constantly increasing linear speed comprising means for suspending a bath of liquid coating material which increases in width toward one end, means for guiding a running thread transversely through said bath and means for so altering the relation of the thread guiding means and the bath that the thread passes through a widening portion of the bath as the linear speed of the thread increases.

10 8. A treating unit for coating a thread running at a constantly increasing linear speed comprising means for suspending a bath of liquid coating material which increases in width toward one end, means for guiding a running thread transversely through said bath and means for shifting the thread guiding means toward a widening portion of the bath as the linear speed of the thread increases.

15 9. A treating unit for coating a thread running at constantly increasing linear speed comprising a pair of spaced blades which increase in width toward one end and between which a bath of liquid coating material which constantly increases in width is adapted to be suspended by capillary attraction, means for guiding a running thread between said blades and through said bath and means for establishing relative movement between the bath and the thread in a direction transversely to the direction of travel of the thread, to increase the width of the bath contacted by the thread as the linear speed of the thread increases whereby a substantially uniform coating is produced throughout the length of the thread.

20 10. A treating unit for coating a thread running at constantly increasing linear speed comprising a pair of spaced blades which increase in width toward one end and between which a bath of liquid coating material which constantly increases in width is adapted to be suspended by capillary attraction, means for guiding a running thread between said blades and through said bath, means for establishing relative movement between the bath and the thread in a direction transversely of the longitudinal axis of the bath to increase the width of the bath contacted by the thread as the linear speed of the thread increases and means to constantly supply the bath with fresh liquid coating material to compensate for that taken up by the thread.

25 11. A treating unit for coating a thread running at constantly increasing linear speed comprising a pair of spaced blades which increase in width toward one end and between which a bath of liquid coating material which constantly increases in width is adapted to be suspended by capillary attraction, means for guiding a running thread between said blades and through said bath, means for so moving the thread that the width of the bath contacted by the thread increases as the linear speed of the thread increases, means to constantly supply the bath with fresh liquid coating material to compensate for that taken up by the thread, and means to so distribute such coating material as to preserve the integrity of the bath.
